UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CASTING-LADLE MECHANISM.

Application filed September 15, 1921. Serial No. 500,849.

To all whom it may concern:

Be it known that I, JAMES B. LADD, a citizen of the United States of America, and resident of Ardmore, in the county of 5 Montgomery, in the State of Pennsylvania, have invented a certain new and useful Improvement in Casting-Ladle Mechanism, of which the following is a true and exact description, reference being had to the accompanying drawings, which form a part thereof.

My invention relates to ladles adapted to contain and deliver molten metal to be used in casting and has for its object to provide 15 the ladle with co-operative mechanism whereby the metal in the ladle can be maintained at a constant level during the pouring so as to insure a flow of metal from the ladle to the mold of constant volume and 20 velocity.

My invention is especially useful for use in connection with centrifugal casting machines of the general type described in the German Letters Patent to Briede, No. 242,- 25 307 of January 4, 1912, but has, I believe, material value for use in other methods of casting.

In my co-pending application filed September 13, 1921 Serial No. 500,831 I have described and claimed an improved casting machine of the general type of the German patent above mentioned and comprising, among other devices, a pouring ladle stationary during pouring and in which the 35 metal is maintained at a constant level and head during the pouring of the casting and in this application I have claimed the use of such a ladle broadly, irrespective of the particular construction of the mechanism 40 by which the result is obtained. My present invention relates to a special construction of mechanism for maintaining the constant level of metal in the ladle and, broadly speaking, it consists in providing a pouring 45 ladle with a displacement body adapted to be moved down into the metal in the ladle as the metal overflows or is withdrawn therefrom and at a rate of speed which will maintain the metal level constant irrespective of the amount of metal remaining in the ladle.

The nature of my invention will be best understood as described in connection with

the drawings in which it is illustrated and in which— 55

Figure 1 is an elevation partly in section showing one form of mechanism embodying my invention.

Figure 2 is a similar elevation showing the same mechanism illustrated in Fig. 1 60 for moving the displacement body but applied in this case to a tilting ladle, and

Figure 3 is a similar elevation showing the application of my invention to a bottom pour ladle and the use in connection therewith of a float with mechanism controlled by a float for regulating the movement of the displacement body in accordance with the rate at which metal is withdrawn from the ladle. 65

A, Fig. 1, is a stationary ladle having a pouring spout indicated at A'. B is a displacement body extending into the ladle and supported by a vertically movable arm C guided at C' on a guideway D' of an 75 upwardly extending standard indicated at D. C² indicates a threaded hole in the arm C in which is screwed a vertically threaded shaft E actuated through a worm wheel E' and shaft F by a motor indicated at G. 80

The mechanism shown in Fig. 2 is generally similar. The ladle, however, is a tilting ladle indicated at H having a pouring spout H' and trunnions H² by which it is supported on standards I. When it is desired to pour from this ladle it is tilted, as shown in full lines in Fig. 2, by the lever arm J' attached to rock shaft J having an arm J² which is pivotally attached at J² to a link J³ and attached to ladle at J² 90 forming a toggle joint which when straightened out, as shown in the drawing, tilts the ladle to a definite degree and holds it in fixed position.

In Fig. 3 the ladle, here indicated at K, 95 is a bottom pour ladle having an outlet K' for the metal, which is opened and closed by a stopper L which, as shown, is connected through an arm L' with a vertical slide L² held in guideways K², K³, and actuated to 100 raise the stopper to a definite degree and lower it, by means of the toggle links i², i³ pivoted to and connected by controlling rod indicated at i'.

In Fig. 3, N is a float partly immersed in 105 the melted metal in the ladle K and sup-

ported on a standard M extending up from the ladle through the parallel motion device consisting of the lever M^2 pivoted to the standard at M' and connected to the float by link M^1 to which is also pivotally attached one arm of a lever M^4 , M^5 , pivoted to the standard at M^3 . The outwardly extending arm M^6 of this lever is connected by a connecting rod O and lever arm O' 10 with a control valve O^2 by which fluid under pressure coming, for example, from the pipe P is directed at will through the pipes P' and P^2 to the opposite ends of the cylinder Q in which works a piston Q' having a piston rod Q^2 attached at C^3 to the arm C . 15

In the construction indicated in Figs. 1 and 2, it is obvious that the motor G if run at constant speed will impart a uniform descending motion to the displacement body 20 B with consequent delivery from the ladle of a uniform stream of molten metal and with maintenance in the ladle of a uniform level.

Referring to Fig. 3, it will also be obvious 25 that the float N and connecting mechanism actuated by the float can be utilized to bring about a downward motion of the displace-

ment body B which will at all times maintain a constant level in the ladle and while in Fig. 3 I have shown a metal displacement mechanism as applied to a bottom pour ladle, it is, of course, obvious that it is equally applicable to pouring ladles of the type shown in Figs. 1 and 2. 30

Having now described my invention, what 35 I claim as new and desire to secure by Letters Patent, is:

1. In combination with a casting ladle, means for maintaining a constant level of the fluid metal in the ladle consisting of a 40 displacement body and means for moving said body into the ladle as metal is withdrawn therefrom.

2. In combination with a casting ladle means for maintaining a constant level of 45 the fluid metal in the ladle consisting of a displacement body, means for moving said body into the ladle as metal is withdrawn therefrom, a float on the metal contained in the ladle and means operated by said 50 float for controlling the mechanism actuating the displacement body.

JAMES B. LADD.
